E. W. BAKER.
FLOOR POLISHING AND WINDOW CLEANING APPLIANCE.
APPLICATION FILED JULY 11, 1916.

1,282,361.

Patented Oct. 22, 1918.

INVENTOR:
E. W. BAKER
BY: *Frank D. Deem*
ATTORNEY.

UNITED STATES PATENT OFFICE.

EDWARD WILLIAM BAKER, OF PALMERSTON NORTH, NEW ZEALAND.

FLOOR-POLISHING AND WINDOW-CLEANING APPLIANCE.

1,282,361.

Specification of Letters Patent.

Patented Oct. 22, 1918.

Application filed July 11, 1916. Serial No. 108,681.

To all whom it may concern:

Be it known that I, EDWARD WILLIAM BAKER, subject of the King of Great Britain, residing at Palmerston North, New Zealand,

5 have invented new and useful Improvements in Floor-Polishing and Window-Cleaning Appliances; and I do hereby declare the following to be a full, clear, and exact description of the same.

10 This invention has been devised mainly with the object of providing means whereby floors may be polished, but which means are also applicable to other purposes such as the cleaning of windows and other surfaces.

15 The invention designed provides for the combination with a handle of any desired length, of brushes adapted to apply polish or water to the desired surface, and a polishing 20 pad for drying or finishing off such surface. It also provides for means whereby an open tin of a polishing preparation may be carried on the handle, and for means whereby the polishing brush may be supplied with a 25 quantity of the polish for applying to the surface as required.

In the accompanying drawings:—

Figure 1 is a side elevation of the appliance with the brush in the position for use.

30 Fig. 2 is a similar view with the brush turned up to receive a supply of polish.

Fig. 3 is a plan of Fig. 1.

Fig. 4 is a front view of the brush.

Fig. 5 is a back view thereof.

35 In carrying out the invention a frame comprised by a pair of side members A and a cross bar B is attached to the lower end of a handle C in such a manner that the side members project from both sides of the handle and form bearing arms to carry respectively the polishing pad D and the brush E.

40 The pad D is made in any approved manner such as to adapt it for the purposes for which the appliance is to be used and may if required, be provided with any of the known means by which a polishing cloth or surface may be secured thereon. It is pivoted between the ends of the arms A on one side of the handle so that it may swing therein and its downward side be changed as desired.

45 The brush E is similarly pivoted between the arms A upon the other side of the handle. This brush may be of any desired design to adapt it for the particular purpose 50 for which the appliance is to be used. In the drawings, a design of brush suitable for

55 applying and spreading a polish paste upon the floor is shown, and consists of a back having a row of fiber E' along one edge of its front and a block of fiber E² in the middle 60 of its other edge.

A coiled spring F is arranged upon the back of the brush by being carried on a spindle G suitably mounted on such brush back. One end of this spring is made fast to the 65 brush back while the other is connected to a suitable point of the frame, as for instance by being threaded through a hole b (Fig. 3) in the cross bar B. The tension of the spring is so adjusted as to turn the brush 70 around in its bearings so that the fiber side is upward, as shown in Fig. 2, and the brush normally turns to such position, when released.

A short rod H is connected at one of its 75 ends to the back of the brush at a point beyond the line of its pivots and the other end of this rod is connected to a flexible wire or Bowden wire J that is carried in suitable guides K up the handle. A lever M is pivoted in brackets N fastened to the handle at a convenient distance from its upper end and the end of the wire J is fastened to this lever. Thus the lever, when turned up, will exert a pull on the wire, and when turned down, will relieve such pull. The upward turning of the lever will therefore by drawing on the wire, turn the brush around on its pivots against the spring's tension, so that its fiber side will be turned out, as shown 80 in Fig. 1, it then being retained in such position by turning the lever in against the handle and beyond the line of pull on the wire. When the lever is turned down and the strain on the wire relieved, the brush 85 will turn up under the influence of its spring F.

A clip O is fixed to the handle C, such clip being adapted to receive and hold a tin or canister by means of a central tongue O' passing up on the inside of the canister's edge, as shown in Fig. 2. The canister is thus held with its opening downward. The clip is so positioned in relation to the brush, that when the brush turns up, a portion 105 thereof will enter the open mouth of the canister held in the clip, as shown by Fig. 2, P representing the canister.

Consequently in the use of the appliance, the brush may be turned up so as to enter 110 the canister and to coat itself with a portion of the canister's contents and may be

then turned down, the appliance reversed and the brush surface applied to the floor so as to spread the material over the floor. Then by again reversing the appliance, the 5 polishing pad D may be rubbed over the treated surface.

I claim:—

1. Means for the purposes described consisting in a handle, a frame extending from 10 the handle, a brush pivoted in the frame adapted to turn up and down therein, a spring upon the brush normally retaining it in the turned up position, a flexible wire extending along the handle and connected to 15 the back of the brush to one side of the line of its pivots and a lever pivoted upon the handle to which the other end of such flexible wire is connected, substantially as specified.

Copies of this patent may be obtained for five cents each, by addressing the "Commissioner of Patents, Washington, D. C."

2. Means for the purposes described consisting in a handle, a frame extending from the handle, a brush pivoted within the frame adapted to turn up and down therein, a clip upon the handle adapted to hold a canister in a position to be engaged by the brush 25 when turned up, a spring upon the brush normally retaining the brush in the turned up position and means upon the handle for turning the brush down, substantially as specified.

In testimony whereof I have signed this specification in the presence of two subscribing witnesses.

EDWARD WILLIAM BAKER.

Witnesses:

E. NEWSON,
E. F. LEAMY.
